UNITED STATES PATENT OFFICE.

VERNON W. HALL, OF PORTLAND, MAINE.

GAME APPARATUS.

1,027,539.

Specification of Letters Patent.

Patented May 28, 1912.

Application filed January 25, 1912. Serial No. 673,477.

To all whom it may concern:

Be it known that I, VERNON W. HALL, of Portland, in the county of Cumberland and State of Maine, have invented certain new and useful Improvements in Game Apparatus, of which the following is a specification.

My invention relates to a game apparatus to be used in connection with rifle practice or target shooting and particularly in connection with indoor shooting with small caliber rifles or revolvers.

The object of my invention is to devise a target for rifle practice by which a game may be played which will give a greater variety than merely counting scores by shooting at a target made up of concentric rings as in the ordinary target shooting. With this end in view I have constructed a target made up of a plurality of spaces each containing the representation of a playing card.

In practice I arrange the target into fifty-two equal squares in each one of which is a centrally disposed spot which is either a heart, club, diamond or spade as used in ordinary playing cards. In the corners of the squares are auxiliary letters or figures which indicate the value of the card.

The game is played in simulation of any game where the comparative value of the hand is determined by the cards held in the hand such as poker and cribbage. Each square struck by a bullet is counted as a card and when the necessary number of shots are made to fill the hand the hand is valued according to the game being played.

The game creates interest and gives variety to target practice and encourages the cultivation of the art of shooting.

In the accompanying drawing I show a representation of a target constructed according to my invention.

A represents the target which is divided into fifty-two squares *a*, each of which has one of the card spots in its center with letters or figures in the corners of the squares to indicate the value of the card. Bullet holes are represented at *b*.

If the game being played was poker, the

five shots fired would indicate the hand to be made up of the king of hearts, the king of spades, the three of diamonds, three of hearts and three of clubs. This would indicate what is known as a "full hand". In the same way the opponent of the player would shoot a hand and the one getting the hand of highest value would be the winner. In the same way the hands may be valued according to the rules of the game of cribbage or any other like game.

The spaces may be of any desired shape, arrangement and number and if desired they may be of unequal size, the higher cards having the smaller spaces so that they will be more difficult to get. This latter arrangement is indicated by dotted lines at *c* and *d* where the ace of hearts is shown as inclosed in a square smaller than the normal size and the king of hearts in a square somewhat larger than that inclosing the ace.

I claim:

1. A game apparatus consisting of a target having a series of spaces each of which contains devices representing a playing card.
2. A game apparatus consisting of a target having a series of spaces of unequal size each space containing devices indicating a playing card, the smaller spaces representing the higher cards.
3. A game apparatus consisting of a target having a series of spaces each of which has in the center thereof one of the spots of a playing card with auxiliary characters indicating the value of the card.
4. A game apparatus consisting of a target divided up into square spaces and having in the center of each space *a*, one of the spots of a playing card with letters and figures in the corners of said squares indicating the value of the cards.

In testimony whereof I have affixed my signature, in presence of two witnesses.

VERNON W. HALL.
